UNITED STATES PATENT OFFICE.

FRED WILLIAMSON EVANS, OF PARK CITY, UTAH.

ATTACHMENT FOR PENCILS AND THE LIKE.

No. 882,377.

Specification of Letters Patent. Patented March 17, 1908.

Application filed March 30, 1905, Serial No. 252,829. Renewed September 21, 1907. Serial No. 393,915.

To all whom it may concern:

Be it known that I, FRED WILLIAMSON EVANS, a citizen of the United States, residing at Park City, in the county of Summit and 5 State of Utah, have invented certain new and useful Improvements in Attachments for Pencils and the Like, of which the following is a specification.

My invention pertains to attachments for 10 pencils; and it contemplates the provision of a novel and advantageous attachment of the type adapted to serve as an eraser, to hold a pencil against casual displacement from the pocket, and to prevent the pencil rolling off 15 an inclined desk or the like.

The invention will be fully understood from the following description and claims when taken in connection with the accompanying drawings, in which:

20 Figure 1 is a view illustrating a pencil equipped with my novel attachment; and Fig. 2 is an enlarged perspective view of the attachment removed.

Similar letters of reference designate 25 corresponding parts in both views of the drawings.

My novel attachment is molded or otherwise formed in one piece of vulcanized rubber, and it comprises a cap-like body A 30 adapted to receive and be held by frictional contact on one end of a pencil B, Fig. 1, and also adapted to serve as an eraser, and three arms C reaching laterally and at right angles from the base of the cap-like body A. The 35 arms C are of V-shape in outline, and hence

the adjacent edges of each pair of arms are adapted to rest at one time upon an inclined desk or the like and thereby effectually prevent rolling of the pencil off the desk. Said V-shaped arms are also adapted, by reason of 40 their stiffness and pointed ends, to engage the walls of a pocket and thereby preclude casual displacement of the pencil from the pocket.

It will be readily appreciated from the 45 foregoing that notwithstanding the practical advantages which I have ascribed to my novel attachment the said attachment is quite as cheap and inexpensive as the ordinary pencil erasers extant and is equally as 50 light and neat in appearance.

Having described my invention, what I claim and desire to secure by Letters Patent, is:—

A pencil attachment formed of one piece of 55 vulcanized rubber and comprising a cap-like body of a size to rest and frictionally retain itself on one end of a pencil, and three equidistant, stiff arms, of V-shape in outline, reaching outwardly at right angles from the 60 base of the cap-like body and having points at their outer ends; the adjacent edges of each pair of arms being arranged to rest at one time on a desk or the like.

In testimony whereof I affix my signature 65 in presence of two witnesses.

FRED WILLIAMSON EVANS.
